UNITED STATES PATENT OFFICE.

JOSEPH M. HOGL, OF WHEELING, WEST VIRGINIA.

WATER GAUGE.

Application filed May 3, 1924. Serial No. 710,880.

This invention relates to water gauges, and more particularly to what I term a double tube glass water gauge.

One of the main objects of the invention is to provide a water gauge of simple and efficient construction which can be produced and applied at relatively small cost. A further object is to provide a gauge so constructed as to insure that the glass water tube will at all times be clear so as to permit the water column to be readily viewed. Another object is to provide simple and efficient means for washing out the gauge so as to remove particles of foreign materials therefrom. Another object is to provide simple and efficient means whereby the glass gauge may be swabed out, when necessary, to remove any film or coating of substances which may collect on the inner surface of the glass tube. Further objects will appear from the detail description.

In the drawings:—

Fig. 1 is a central vertical section through the gauge;

Fig. 2 is a central vertical section through the gauge taken in a plane at right angles to Fig. 1.

The gauge includes an upper head 1 and a lower head 2 which may be termed the steam head and the water head, respectively, for convenience of description. The head 1 is provided with a central nipple 3 connected by coupling 4, or in any other suitable or preferred manner, to a nipple 5 which communicates with the steam space of a boiler in connection with which the gauge is used. Nipple 3 communicates with the head 1 by means of an opening or port 6 which is provided with a valve seat 7 for reception of a valve 8 provided with a stem 9 which threads through a nipple 10 extending from the opposite side of head 1 to, and in alignment with, nipple 3. A suitable operating wheel 10^a is secured on the outer end of valve stem 10. A packing gland 11 is positioned about the outer portion of valve stem 9 so as to form a fluid tight closure about the same, as is known. This provides simple and efficient means for controlling communication between the steam space of the boiler and head 1.

Head 2 is constructed similarly to head 1 and is connected by means of a nipple 3^a and coupling 4^a to nipple 5^a which communicates with the water space of the boiler. This head is also provided with a valve 8^a

similar to the valve mounted in head 1 and including a stem 9^a threaded through packing gland 10^a and provided at its outer end with a wheel 10^b for controlling communication between head 2 and nipple 3^a. Each of the heads 1 and 2 is provided, adjacent to one end, with a nipple 12 which is directed toward the other head, and each head is further provided adjacent to its other end with a similarly directed nipple 13. Each of the heads is also provided with two nipples 14 and 15 which are disposed at the opposite side of the head to nipples 12 and 13 and in alignment therewith. The nipples 12 receive the end portions of a brass tube 16 with the upper end of which contacts a plug 17 threaded through the upper nipple 14 of head 1. This plug is provided, in its lower end portion, with a recess 18 with 75 which communicate a plurality of openings 19 extending through the plug and positioned closely adjacent to the lower end thereof.

As will be noted more clearly from Fig. 2, the upper end of tube 16 is flush with the inner face of the bottom of head 1 and the openings 19 are positioned closely adjacent to the bottom of this head. The lower end portion of tube 16 extends through nipple 12 of head 2 and is secured therein by a 80 packing gland 20 which also serves to form a fluid tight closure about the tube, a similar packing gland 21 being mounted on nipple 12 of head 1. The lower end of tube 16 is bored to provide a valve seat 22 for reception of a valve 23 provided at the upper end of a hollow stem 24 threaded through neck 25^a of a valve casting 25 and provided at its lower end with a hand wheel 24', this neck being threaded through nipple 14. 95 Stem 24 is provided with a plurality of ducts 24^b which communicate with bore 24^b of stem 24 adjacent to the lower end thereof, this bore extending approximately one-half of the length of the valve stem. A petcock 26 communicates with casing 25 and provides means for permitting escape of water from the casing when desired. A glass tube 27 has its end portions mounted in nipples 13 of heads 1 and 2 in the same manner as tube 16 is mounted. A plug 28 similar to but shorter than plug 17 is threaded through nipple 15 of head 1 and bears upon the upper end of tube 27. As will be clear from Fig. 2, the ducts 28^a of plug 28 are positioned adjacent to the upper wall or top of head 1. Head 2 is provided, at the lower

end of nipples 13, with an inwardly projecting shoulder 13^a which forms a seat for the lower end of glass tube 27. A closure plug 29 is threaded into nipple 15 of head 2 and acts to normally close this nipple, this plug, for convenience of operation, being provided with a stem 30 on the lower end of which is secured a hand wheel 31. As will be readily understood, packing glands and gaskets are employed wherever necessary or desirable and these members may be of any suitable or preferred construction. In practice the gauge is applied to a boiler in a well known manner, the valves of both heads 1 and 2 being opened so as to obtain equalization of pressure. The water in glass tube 27 is readily visible to indicate the water level in the boiler. If the gauge should become obstructed or the glass tube 27 becomes soiled, the gauge may be readily washed out. To wash the gauge out the water valve in head 2 is first closed, valve 23 is turned into closed position so as to seat in the lower end of brass tube 16, and the steam valve of head 1 is then closed after which the water valve of head 2 is opened, petcock 26 being also opened. This permits hot water to flow upwardly through tube 27 into head 1 then down through tube 16, valve 23 and valve stem 24 into valve casing 25 through the ports 24^a. This water escapes from valve casing 25 by means of petcock 26. This provides simple and efficient means whereby the gauge can be readily washed out to remove any film or coating which may collect on the inner face of glass tube 27. By having the ports 28^a of plug 28 positioned adjacent to the top of head 1, and the ports 19 of plug 18 adjacent to the bottom of this head, any sediment or other foreign materials which may be deposited in head 1 will escape through tube 16. This avoids, to a great extent, clouding or coating of glass tube 27 and also eliminates danger of clogging or stoppage of this tube. After the gauge has been thoroughly washed out in the manner stated, petcock 26 is closed, valve 23 is opened and the steam valve of head 1 is opened, the steam and

water valves being both adjusted properly to insure best operation of the gauge. In the event that the inner surface of tube 27 becomes coated with a film or covering as might occur when using water containing excessive amounts of foreign materials, it may become necessary to swab out the tube with chemicals prepared for this purpose. This may be readily done by closing both the steam valve and the water valve and opening petcock 26, after which plug 29 is removed and tube 27 is swabbed out. After the tube has been properly cleaned, plug 29 is replaced and petcock 26 is closed, the water and steam valves being then opened to permit the water to flow into the gauge. This may be quickly and easily done without interfering to any appreciable extent with the use of the gauge or effecting its operation.

What I claim is:—

In a water gauge, an upper head, a lower head, control valves for the respective heads, two tubes establishing communication between the heads, a hollow member extending from the top of the upper head and bearing upon the upper end of one of the tubes, said member being provided with openings positioned adjacent to the bottom wall of the upper head, a similar member contacting with the upper end of the other tube and being provided with openings positioned adjacent to the top wall of the upper head, a valve casing secured to the lower head in alignment with one of the tubes, an outlet valve threaded through said casing for establishing and cutting off communication between said first mentioned tube and the lower head, the outlet valve being provided with a bore extending from its inner end and with openings extending from this bore and establishing communication between the same and the valve casing, and an outlet member communicating with the valve casing.

In testimony whereof I affix my signature.

JOSEPH M. HOGL.
